[57] CLAIM

The ornamental design for sun visor for a catcher's mask, as shown and described.

DESCRIPTION

FIG. 1 is a top plan view of a sun visor for a catcher's mask showing our new design;
FIG. 2 is a bottom plan view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top, front and left side perspective view thereof, with the tab in the open position;
FIG. 8 is a bottom, rear and right side perspective view thereof, with the tab in an open position; and,
FIG. 9 is a perspective view thereof mounted on a catcher's mask, the catcher's mask shown in broken lines is for illustrative purposes only and forms no part of the claimed design.
